(57) **CLAIM**

The ornamental design for a handbag as shown and described.

DESCRIPTION

FIG. 1 is a perspective view of a handbag showing our new design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures and the areas within the broken lines show grayed-out portions of the handbag that form no part of the claimed design.
